Attorney.

UNITED STATES PATENT OFFICE.

VALENTIN SCHLÄFER, OF SOMMERDA, GERMANY, ASSIGNOR TO RHEINISCHE METALL-WAAREN- UND MASCHINENFABRIK, OF DUSSELDORF-DERENDRÖF, GERMANY, A CORPORATION OF GERMANY.

FUSE FOR PROJECTILES.

Application filed November 19, 1924, Serial No. 750,894, and in Germany December 1, 1923.

In fuses for projectiles for firing at aircraft at great heights, the arrangement has already been proposed by which the inflammable material of the composition ring is not in connection with the external air by radially and externally directed borings or passages, since in consequence of the great speed of rotation in conjunction with the greatly diminished density of the air in the upper strata of the atmosphere, the introduction of the oxygen necessary for the combustion of the powder is decreased and is so reduced that combustion of the material of the ring is delayed and the flame may even be extinguished. Instead of lateral openings for introducing air to the composition rings, a longitudinal passage has been provided which leads into a conical shaped space open in front. The air in the hollow space and the passage leading therefrom to the composition is compressed in consequence of the high forward velocity. The initial ignition device was protected on that account within the hollow cap shaped discharge space for the fuse gases by a cap completely closing it in the usual manner against external influences.

Air must, however, be allowed to enter at the point of the fuse at the beginning of the flight of the projectile. The entrance of foreign bodies, of dust, moisture and the like to the composition rings must, however, be prevented during the mounting and while protected before actual use, in order to prevent the passages for introducing the air from being choked and to prevent any change of the particles of the ignition composition. If the front opening of the fuse body was closed for this purpose, this closing device must be removed before using the projectile; this might be forgotten, in any case was troublesome, and in fact and for that reason such a closing device has not up to the present time been in use.

The invention provides such device, but ensures that no special manipulation is required, in order that at the moment of firing air should be introduced into the interior of the fuse. A thin small plate is secured in known manner at the circular opening of the fuse, as has previously been known in fuses with plungers, but in this latter case it serves a different purpose and must be intact during the flight of the projectile in

order to keep off the air pressure from the plunger, and only at the moment of impact of the projectile, and by means of this is destroyed. The invention consists, therefore, in the employment of a small closing plate for the front opening by which air is introduced into the fuse, which is independent of the necessary covering of the ignition device by a protecting cap, and in the automatic disruption of this plate at the moment of firing the projectile and in the means for accomplishing this.

The accompanying drawing represents two embodiments of the invention.

In Fig. 1 the closing cap *b* surrounding the plunger *a* has several lateral or laterally inclined passages *c* which connect the interior of the cap with the hollow space *d* surrounding the cap, from which space a longitudinal air passage *e* leads to the composition *f*, while the space at the forward end, according to the invention, is separated from the external atmosphere by a small plate *g*. The number, position and direction of the lateral or laterally inclined passages *c* in the covering cap *b* are determined so as to prevent the total area being large enough to prevent the cap from efficiently protecting the sensitive portion of the fuse. The plunger *a* is provided with a longitudinal boring *h* extending as far as the detonator *i*. As soon as the fuse is penetrated, that is, when on firing the plunger pierces the primer, gas is generated from the composition in the detonator *i*, the combustion gases pass through the boring *h* of the plunger and the openings *c* in the cap into the hollow space *d* and their pressure bursts or tears open the small plate *g* separating this space from the external air, and thereby immediately opens the path for the external air to the interior of the fuse.

Figs. 2 and 3 show a modified construction. In this case the closing plate *g* is not destroyed by the pressure of the existing gases of combustion, but the plunger *a*, which need not be bored, is soldered or otherwise fastened to the plate *g*. On the relative backward movement of the plunger due to the initial shock on firing the projectile, the small plate *g* will be taken with the plunger being drawn out of or torn from its peripheral fastening and will thereby establish a free opening at the front end of

the hollow space d , and consequently communication with the external air.

Fig. 2 shows the position of the parts before firing and Fig. 3 just after firing.

The invention which is described above for a time fuse can naturally also be employed in combination fuses with time and impact ignition.

I claim:

1. A fuse for projectiles for firing at objects at great heights comprising a fuse body having an opening therein which leads by means of a passage to the fuse composition; a thin plate in the forward end of said opening; and means for automatically breaking said plate when the projectile is fired in order to allow the atmosphere to penetrate into the fuse body and to the fuse composition by means of said passage.
2. A fuse for projectiles for firing at objects at great heights comprising a fuse body having an opening therein provided with a thin closure; and means for automatically breaking said closure when the projectile is fired in order to allow the atmosphere to penetrate into the fuse composition, said closure being thin in order that it may be easily and instantaneously disengaged by said means when the projectile is fired.
3. A fuse for projectiles for firing at objects at great heights comprising a fuse body having an opening therein provided with a thin plate; a fuse composition in said body and having an air passage cooperating therewith; a detonator in said body; and means when the projectile is fired to fire the detonator so that the gases generated by the detonator will break the thin plate in order to allow the atmosphere to penetrate to the fuse composition.
4. A fuse for projectiles for firing at objects at great heights comprising a fuse body having an opening therein; a thin plate secured in said opening; a fuse composition in said fuse body; a detonator in said body; and a plunger in said body adapted to cause the detonator to fire when the projectile is

fired, so that the gases generated by the detonator will break the thin plate in order to allow the atmosphere to penetrate to the fuse composition.

5. A fuse for projectiles for firing at objects at great heights comprising a fuse body having an opening therein; a thin plate secured in said opening; a fuse composition in said fuse body; a detonator in said body; a plunger in said body adapted to cause the detonator to fire when the projectile is fired so that the gases generated by the detonator will break the thin plate in order to allow the atmosphere to penetrate to the fuse composition; and a closing cap having perforations therein fitted over said plunger.

6. A fuse for projectiles for firing at objects at great heights comprising a fuse body having an opening therein; a thin plate secured in said opening; a fuse composition in said fuse body; a detonator in said body; a plunger in said body adapted to cause the detonator to fire when the projectile is fired, so that the gases generated by the detonator will break the thin plate in order to allow the atmosphere to penetrate to the fuse composition; and a closing cap having perforations at the sides fitted over said plunger in order to protect it.

7. A fuse for projectiles for firing at objects at great heights comprising a fuse body having an opening therein; a thin plate secured in said opening; a fuse composition in said fuse body, said body having an air passage therein communicating with said fuse composition; a detonator in said body; a plunger in said body adapted to cause the detonator to fire when the projectile is fired, so that the gases generated by the detonator will break the thin plate in order to allow the atmosphere to penetrate to the fuse composition; and a closing cap having perforations at the sides fitted over said plunger in order to protect it.

In testimony whereof I have affixed my signature.

VALENTIN SCHLÄFER.
